his attorney.

UNITED STATES PATENT OFFICE

LOUIS D. GIBSON, OF NORWAY, MAINE, ASSIGNOR TO W. F. TUBBS COMPANY, OF NORWAY, MAINE, A CORPORATION OF MAINE

SKI BINDER

Application filed April 17, 1928. Serial No. 270,674.

My invention relates to ski binders of the type having adjustable toe irons.

An object of my invention is to provide a ski binder which may be readily adjustable 5 to suit the width of the wearer's shoe.

Another object of my invention is to provide a ski binding of the class described in which the adjustment is easily and readily varied and in which the adjustment is permanent.

Another object of my invention is to provide a device of the class described which may be easily applied to the ordinary types of skis.

These and other objects of my invention will become more apparent from the following description of an embodiment thereof, reference being had to the accompanying drawings forming a part of this specification.

Referring to the drawings:

Fig. 1 is a side elevational view showing the connecting straps;

Fig. 2 is a plan view with the straps removed;

Figs. 3, 4 and 5 are plan views of the interlocking members which make up the toe plate;

Fig. 6 is a vertical medial sectional view of the device of my invention; and

Fig. 7 is a perspective view of one of the members of Fig. 4.

Referring now to the figures of the drawings, wherein like parts are designated by like reference characters, at 1, I show a portion of a wood ski. It will be noted that the 25 ski illustrated does not have a transverse slot projected through it from side to side to receive portions of the binding as in other constructions. I preferably omit this slot, mounting the binding hereinafter described

40 comprising side clamps 3 and 4, of which two are provided, on the upper surface of the ski. As best shown in Figs. 3 and 5, the clamps are oppositely disposed on the right and left sides of the ski upper surface, and each comprises a quadrilateral bottom plate 6 and 6', respectively, which are wider toward the rear portions thereof. The rear edge of each is notched to provide a series of teeth shown at 7 and 20, respectively. At the side of each bottom plate an upwardly extending flange,

shown respectively at 14 and 14', is provided, which extends rearwardly at 5 and 5', to support pairs of buttons 8, 8', 9 and 9', riveted thereon. From the vertical flanges, inwardly extending lateral retaining flanges 11 and 11' project, and are adapted to receive the toe strap 24 later described. Slots 12 and 12' are provided running transversely of the base flanges of the plates. Each plate is notched at 13 and 13' in the edge opposite to the upwardly extending flange. The retaining flanges 11 and 11' are adapted to fit over the thick shoe sole of the user and to assist in rigidly securing the ski binding to the user's foot.

The two side clamps are adapted to be held on to the ski by a clamping plate, as best shown in Fig. 7, which comprises a piece of sheet metal 17 in preferably the shape of a trapezoid. The opposite parallel edges 18 and 19 are bent downward to form short depending flanges. The rear flange 19 is cut away in portions to form a plurality of downwardly bent lugs, or teeth.

The two side clamps are placed in their respective positions substantially as shown in Fig. 2, and the plate 17 placed on top of them. The front flange will engage the forward edges and the flange 19 with the depending teeth will engage the notches 7 and 20, respectively, locking the side clamp against accidental movement. Screws are then inserted in the holes 21, 22 and 23, which align with the slots 12 and 12' and the notches 13 and 13', and are screwed into the wood of the ski to clamp the parts together and securely to the ski.

The width of the assembled clamp may be varied to suit the wearer's shoe by loosening the screws and disengaging the lugs on the plate 17 from the notches 7 and 20 in the side clamp and sliding the clamps outward to the desired width whereupon the screws are again tightened and the lugs engage the notches and prevent further movement.

Although I have shown a wooden ski with screws as the means of attachment, I may use bolts secured in any convenient way, such as by being threaded into metallic interiorly threaded sockets, commonly known as "screw-

holes," embedded into the wood ski, and I do not desire to limit any invention to the use of wood skis as it may be applied to metal skis as efficiently as to wood.

5 A toe strap may be provided, as shown in Fig. 1, at 24, having a buckle 25. This strap is looped at both of its ends through the openings 10 and 10' provided by the shearing of the lugs 11 and 11' from the side plates 10 3 and 4. A heel harness 26, having a buckle 27 and a clamp 28 is also provided to engage the heel and includes the strap 29 and buckle 30 which passes over the instep. The harness is attached to the clamp assembly by hooks fastened to the end of the straps, which are hooked over the buttons 8 and 8' and prevented from accidental displacement by the buttons 9 and 9', as shown. The buckles furnish means of adjusting the strap to suit 15 the shoe of the wearer and the clamp 28 furnishes a quick means of releasing the straps.

Having thus described my invention in a preferred embodiment, I am aware that numerous and extensive departures may be 20 made from the embodiment herein illustrated and described but without departing from the spirit of my invention.

I claim:

1. In a ski binder in combination with a 30 ski or the like, toe plates including lateral attaching portions and vertical supporting portions, a clamping plate, said toe irons being provided with transverse slots intermediate the lateral portion and a plurality of notches 35 in the rear edge, said clamping plates being provided with a plurality of holes adapted to align with said slots in said toe plates and a plurality of downwardly extending lugs, said notches adapted to be engaged by said lugs to prevent relative movement between 40 said clamping plate and said toe plates, means to hold said binder to said ski.

2. In a ski binder, the combination with a 45 ski, a pair of toe plates each comprising a laterally extending portion having a transverse slot therein and provided with a plurality of notches in the rearward edge thereof, flanges extending upwardly and rearwardly from one side of each iron, a 50 clamping plate having parallel apertures thereof bent downward to form a front and rear depending flange, said rear flange being cut away in portions to form a plurality of lugs, said clamping plate adapted to engage 55 said toe plates and prevent accidental movement thereof, means to hold the clamping plate to said ski, said upwardly extending flange being apertured to receive a toe strap, said flange adapted for connection 60 with the heel strap of the ski.

3. In a ski binder, in combination a pair 65 of relatively laterally disposed side plates, each of said side plates comprising an upstanding laterally disposed flange, means carried by each flange for connection with

the heel strap of the ski, a clamping plate adapted to be superposed over each of the side plates, said clamping plate being perforated to admit a securing screw adapted to be projected therethrough and between the inner jaws of the said plate elements into the ski, and interlocking means for the clamping plate and side plates adapted to secure the side plates against outward lateral displacement in a given adjusted position relative to the clamping plate, said interlocking means for the superposed plates, comprising projections of one of the plates extending within certain of a series of transversely disposed slots in the other plate, according to 70 the desired adjustment.

4. In a ski binder, a toe plate therefor comprising three pieces, two of the pieces having upstanding side flanges, and the third piece adapted to be disposed in superposed relation to the contiguous portions of the other pieces, and means comprising integral portions of superposed pairs of said pieces adapted to interlock to prevent relative lateral movement thereof when disposed in any 80 of a plurality of lateral relatively adjusted positions.

5. In a ski binder, in combination, of a pair of side plates therefor having flanged portions adapted to be secured to a transverse surface of the ski, and a clamping plate for said flanges disposed in superposed relation thereto, said clamping plate and said flanges being each provided in a transversely extending edge portion with interlocking teeth, and means to secure the clamping plate to the 90 ski.

6. In a ski binder, in combination, a pair of side plates therefor having flanged portions adapted to be secured to the upper surface of the ski, and a clamping plate disposed on top of said flanges, said clamping plate and said flange being each provided in a transversely extending edge portion with interlocking teeth, and means to secure the 100 clamping plate to the ski.

In testimony whereof I hereunto affix my signature this 17th day of March, 1928.

LOUIS D. GIBSON. [L. S.]
